LOUIS B. HASBROUCK, OF ELMIRA, NEW YORK, ASSIGNOR TO ECLIPSE TEXTILE DEVICES, INC., OF ELMIRA, NEW YORK, A CORPORATION OF NEW YORK

TENSION DEVICE

Application filed February 18, 1928. Serial No. 255,239.

This invention relates to tension devices, and aims to provide a simple device of this character in which the tension may be varied.

5 A tension device embodying the invention in the form which I consider most desirable includes two separate tensioning elements, one of which applies pressure to a traveling yarn, and the other of which changes the direction of travel of the yarn. The two elements of the device are so connected that the tension of the yarn is varied by simultaneously varying the pressure applied by one element, and the angle of the change in direction produced by the other element.

In order that the invention may clearly be understood, I will describe in detail a specific tension device embodying it, which is shown in the accompanying drawings in which:

20 Fig. 1 is a side elevation of the tension device showing it adjusted for maximum tension;

Fig. 2 is a similar view showing an adjustment for reduced tension;

25 Fig. 3 is a side elevation taken from the opposite side from Figs. 1 and 2; and

Fig. 4 is a plan view showing the supporting frame sectioned on the line 4—4 of Fig. 3.

The tension device illustrated includes, in addition to its supporting plate 60, a horizontal bed 61 having a vertical arm 62 attached to the plate 60 by means of a horizontal pivot 63, a rotatable tension disc 64 resting on the bed 61 and pivoted on a rod or pin 74 fixed to the bed 61, and a tension bar 65 carried by a projection 66 extending laterally from the arm 62. The bed 61 contains slots 61a to permit the escape of any dirt removed from the yarn as it passes between the bed and the tension disc.

To facilitate the threading of the tension device, the bed 61 is provided with ears 67 which guide the yarn into a slot 69 extending under the tension disc 64, and the tension rod 65 is provided with a bent end portion 70, which extends over the tension disc and beyond the slot 69. In threading the tension device, the yarn is dropped between the two ears 67, drawn against the extension 70 until it slips under the tension rod 65, and

is then passed over a thread guide 23. The lower surface of the tension rod 65 lies in substantially the same plane as the upper surface of the bed 61, so that, as the yarn slips under the rod 65, it also slips under the disc 64; and after the tension device is threaded, the yarn is drawn evenly across the upper surface of the bed 61, and then around tension rod 65.

The tension placed on the yarn is adjusted by varying the angle through which the yarn changes its direction in passing across the tension rod 65. To reduce the tension, the arm 62 is turned about the pivot 63 so as to increase the angle B between the reach of the yarn traveling toward the tension rod 65 and the reach of the yarn traveling away from this rod, and at the same time to decrease the pressure of the disc 64 by inclining the disc pivot rod 74 from the vertical. (See Figs. 1 and 2.) The arm 62 may be held in any adjusted position by means of a screw 72 passing through a slot 73 in the arm and entering the supporting plate 60. It should be noted that such adjustment of the tension does not interfere with the alignment between the upper surface of the plate 61 and the lower surface of the tension bar 65.

What I claim is:

1. An adjustable tension device, comprising cooperating members providing opposed surfaces between which the yarn is drawn, a rod positioned with one of its sides in approximately the same plane with one of said surfaces, a thread guide positioned to guide the yarn from the opposed surfaces across the rod, and means whereby the cooperating members and the rod may tilt to change the angle at which the yarn passes around the rod while maintaining the alignment between one side of the rod and one of the opposed surfaces.

2. An adjustable tension device, comprising a bed over which the thread passes, a pivot pin fixed on the bed, a tension disc rotatably mounted about the pivot pin, a tension rod positioned with one of its sides in approximately the same plane as the bed, a thread guide beyond the rod and out of said plane, and mounting means whereby the bed and the

rod may be tilted about an axis in fixed relation to said thread guide to change the pressure of the tension disc and the angle at which the yarn passes around the rod.

3. A tension device, comprising a frame, a bed secured to said frame over which the thread passes, a pair of ears projecting from one side of said bed, a pivot pin rising from the center of said bed, a tension disc rotatably mounted about said pivot pin, a rod projecting from the frame at the side of the bed opposite to the ears and having its lower surface in the same plane as that of the upper surface of the bed, and an extension from the outer end of said rod inclined inwardly toward the frame and upwardly to a point directly above the tension disc and as near the frame as the opening between the said ears.

4. A tension device, comprising a fixed member, a member pivoted to said fixed member, a gravity pressure-applying element mounted on said pivoted member, a direction-changing element mounted on said pivoted member, and a thread guide fixed on said fixed member, whereby the tension on a thread passing through said gravity pressure-applying element across said direction-changing element and over said thread guide may be varied by pivotal adjustment of said pivoted member with respect to said fixed member.

5. A tension device, comprising pressure-applying elements mounted to pivot about an axis, a direction-changing element following said pressure elements in the path of the thread and mounted to pivot on the same axis as the pressure elements, and a guide following said direction-changing element and mounted in fixed relation to the pivot of said pressure and direction-changing element.

In testimony whereof I have hereunto set my hand.

LOUIS B. HASBROUCK.
